NAIL DISTRIBUTOR

Orin L. Smith, Swampscott, Mass., assignor to
United Shoe Machinery Corporation, Paterson,
N. J., a corporation of New Jersey

Application March 14, 1932, Serial No. 598,632

15 Claims. (Cl. 1—39)

This invention relates to the class of apparatus, commonly termed nail-distributors, which effect the delivery of nails in successive loads, each containing a predetermined number and with their heads and points definitely arranged.

It is an object of my invention to render the delivery from the apparatus more reliable, especially when short nails are being operated upon, and to increase the ease of actuation of certain elements.

A feature of my invention leading to the attainment of this object involves novel means for positioning the nails in their travel through the apparatus, especially having to do with the reversal of nails which are not arranged as desired. One of two associated nail-supporting members, for example a nail-conveyor or raceway and a reversing device above which the points of the nails descending the raceway are directed, is provided with means as a depression formed in it, this acting upon the heads of the nails to present the points above the nail-supporting surface of the other member. In the illustrated embodiment of the invention, a downwardly inclined raceway has upper and lower sections, in which are nail-conducting grooves with a nail-reversing bar extending above the upper portion of the lower raceway, there being depressions in the grooves of the upper raceway adjacent to its lower extremity to receive the heads of the nails. When nails are proceeding down the upper sections points first and it is desired to reverse them at the bar, the nail-heads enter the depressions. This lowering of the heads insures the passage of said points above the bar and their deflection heads-down to the lower raceway-section.

A further feature of the invention concerns the controlling of the delivery of the nails from the distributor. With a movable discharge device, which may be an oscillatory roll, I combine a bar or other stop member arranged for contact with nails resting upon such device and movable transversely of the discharged nails, the movement being effected preferably by such means as a cam movable with the discharge device. The stop member is herein shown as pivoted above the discharge device at its opposite extremities, being mounted upon arms turning upon the nail-conveyor, at the delivery-end of which the discharge device is located. In the preferred roll-form of this discharge device, it is provided with passages for the nails and with a surface over which said nails are delivered. The stop member or bar is movable toward and

from this surface to either retain the nails in the passages or to permit their delivery therefrom. The stop, by this delivery-movement, is carried wholly clear of the roll, leaving no space in which nails are liable to catch and clog. The manner of mounting the stop member is such that it offers little resistance to movement, absorbing but a small amount of power. To adapt the organization for satisfactory operation upon nails of different lengths, the stop member is variable as to its normal position, as by adjustably pivoting it upon its carrier-arms.

For the purpose of disclosing my invention, a particular form is illustrated in the accompanying drawing, in which

Fig. 1 shows in broken side elevation a nail-distributor embodying the invention;

Fig. 2 is an enlarged longitudinal sectional detail at the reversing bar;

Fig. 3, an enlarged broken side elevation of the stop member and its mounting;

Fig. 4, a broken front elevation of said stop member; and

Fig. 5 is an enlarged transverse vertical section through the raceway at the depressions.

Generally, the organization may be as in Letters Patent of the United States No. 1,005,303, Pope, October 10, 1911. The nails to be fed are delivered from a rotary drum 19 upon a downwardly inclined vibratory conveyor or raceway 12 movable upon a frame 14, in which raceway are a series of parallel nail-conducting grooves 16, each of which is V-shaped in cross-section. The raceway is divided into upper and lower sections 18 and 20, respectively, and between these sections is a reversing device furnished by a bar 22 extending across the upper extremity of the lower section adjacent to the delivery-end of the upper section. Nails traveling down the section 18 of the conveyor heads first overbalance at the end of said section, without engagement with the reversing bar, and continue on their way along the section 20. When the lighter portion or point of a nail is in advance, it should pass above the bar and be held up by a surface 24 thereon, so, when the head leaves the upper section, it falls and the nail is reversed, causing all those upon the lower section to lie in the same direction. It is found, however, that when short nails of the character of that shown at N in Fig. 2, having heads of considerable diameters, are advanced points first along an upper raceway-section having a uniformly inclined surface, said points, upon leaving the upper section, may be so directed downwardly

under the influence of the head that they may lie below the upper surface of the bar, in position to contact with its rear wall. In such case, they fall and proceed points first over the lower section and are thus delivered in the wrong relation. This cannot be successfully overcome by adjustment of the reversing bar closer to the end of the upper raceway-section, because the nails having their heads in advance may then 5 catch upon the bar and be incorrectly reversed. I overcome this tendency of the nail-points to fail to bridge the space between the raceway-end and the top of the reversing bar, by forming in each wall of the V-grooves of section 18 a 10 depression 26 which, at its portion of maximum depth is located at a distance from the juncture of the nail-point-supporting surface 24 with the rear wall of the bar somewhat greater than the length of the short nails which are likely to be 15 misfed. The depth of each depression is preferably somewhat less than that of the groove, and such that the descent of the heads into it will elevate the points and prevent them from being directed downwardly as they pass beyond the 20 section 18, so as they approach the bar, said points travel above the surface 24. The forward ends are thus supported so the reversal is effected, and short as well as long nails are all received heads first upon the lower raceway-section. 25 Due to the fact that the apex of the V-groove 16 in each raceway is preserved below the depression 26, control is maintained of both cut nails and the points of headed nails as they travel through the depression. This guards 30 against their lateral displacement.

At the end of the raceway-section 20, the delivery of the nails in successive groups is controlled by a discharge-device. This may consist of the well-known roll 28 journaled at opposite 35 sides of the section. An example of a discharge-device of this type may be seen in Letters Patent of the United States No. 1,558,481, Hudson, October 27, 1925. In the roll is a series 40 of passages 30, one normally aligned with each raceway-groove 16. The forward extremities of 45 the passages open through an approximately vertical surface 32 at one side of a sector-shaped space in the roll. At the other side of the space is a surface 34 continuing the passages 30 and 50 supporting the nails as they are delivered. The roll is operated between the position shown in Fig. 3 of the drawing, in which the nails are received from the conveyor-grooves, to one in which the surface 34 is so inclined downwardly 55 that the nails are discharged into tubes 36, by connections 37 actuated by a cam 38 upon a power-shaft 40 of the apparatus. To retain the 60 nails in the first-mentioned position of the roll, ready for delivery when its anti-clockwise movement occurs, a stop member is provided. Rotatably mounted upon the delivery-end of the raceway-section 20 is a shaft 42 having fast upon 65 each extremity an arm 44. Arranged to turn in the arms above the discharge-roll 28 is a spindle 46, to which is secured a bar 48 with its lower edge lying normally in proximity to the roll-surface 34. The position of this edge from front to 70 rear of the surface is determined by a contact-screw 50 threaded through an arm 52 clamped to the spindle near one end. A torsion-spring 54, 75 connected to the opposite end of the spindle, urges the screw against the upper surface of a boss 56 projecting from the inner side of the adjacent arm 44. The location of the axis of the spindle 46 longitudinally of the apparatus

and its distance above the discharge-roll-surface 34 are such that the lower edge of the bar 48 is caused to move in a path closely paralleling said roll-surface. The bar may thus be carried toward and from the inner extremities of the nail-passages 30, adapting it to stop nails of different lengths in the proper relation to the end of the raceway-section 20 to allow their delivery upon the oscillation of the roll while the succeeding nails are retained upon the raceway. For this delivery, the stop-bar 48 should be removed from the path of the nails which are to descend over the surface 34. This is preferably accomplished by swinging up the arms 44 about the axis of the shaft 42 in the proper time-relation to the oscillation of the roll. I have shown this as accomplished by a cam-projection 58 upon the discharge-roll 28, the end of the projection engaging a contact-surface 60 upon the under side of one of the arms 44. The edge of the bar is thereby carried away from the surface 34 transversely of the path of the nails almost at right angles to it, completely freeing said surface for the discharge and leaving no retaining wall against which said nails may accumulate and clog the apparatus. Moreover, the bar is so situated and actuated that the resistance to its movement is slight, it operating smoothly, without danger of cramping, with minimum wear and requiring the application of little power.

Having described my invention, what I claim as new and desire to secure by Letters Patent of the United States is:

1. In a nail-distributor, associated nail-supporting members separated by a space bridged by the nails as they travel from one member to the other, one of the members having a depression arranged to receive the heads only of the nails and thereby present the points above the plane of the nail-supporting surface of the other member.

2. In a nail-distributor, associated nail-supporting members separated by a space bridged by the nails as they travel from one member to the other, one of the members being provided with means arranged to act upon the heads of the nails only to present the points above the plane of the nail-supporting surface of the other member.

3. In a nail-distributor, a raceway provided with positioning means arranged to lower the heads of nails traveling along the raceway, and a reversing device having a rear wall above which the points of the nails pass while they are under the influence of the positioning means and a surface extending forwardly from said wall to receive the points of the nails.

4. In a nail-distributor, a grooved raceway in which is a depression in the walls of the groove, and a reversing device beneath which pass nails delivered from the raceway and above which the points of the nails are directed while the heads are in the depression.

5. In a nail-distributor, a downwardly inclined raceway having upper and lower sections in which are nail-conducting grooves, there being means associated with each groove arranged to lower the heads of the nails, and a nail-reversing device above which pass the points of the thus-positioned nails.

6. In a nail-distributor, a downwardly inclined raceway having upper and lower sections in which are nail-conducting grooves, there being a depression in each groove adjacent to its lower extremity, and a nail-reversing bar extending above the upper portion of the lower raceway-section.

7. In a nail-distributor, a discharge device movable to deliver nails therefrom, a nail-stop arranged for contact with nails resting upon the discharge device, said stop being movable transversely of the nails upon the discharge device, and means for moving the stop to free the nails for delivery from the discharge device. 5
8. In a nail-distributor, a discharge device movable to deliver nails therefrom, a nail-stop 10 having a bar situated above and extending longitudinally of the discharge device, the stop-bar being movable transversely of the nails upon the discharge device, and means movable with the discharge device for moving the stop-bar away from the discharge device to free the nails for delivery. 15
9. In a nail-distributor, a discharge device movable to deliver nails therefrom, a nail-stop co-operating with the discharge device, said stop being movable transversely of the nails upon the 20 discharge device, means for moving the stop to free the nails for delivery, and means arranged to vary the normal relation of the stop to the discharge device.
10. In a nail-distributor, a nail-conveyor, a 25 discharge device co-operating with the delivery-end of the conveyor, arms pivoted upon the conveyor, a stop-bar carried by the arms and movable into and out of nail-retaining relation to the discharge device, and bar-actuating means movable under the power of the distributor and acting upon one of the arms. 30
11. In a nail-distributor, a nail-conveyor, a discharge device co-operating with the delivery-end of the conveyor, arms pivoted upon the conveyor, a stop-bar carried by the arms and movable 35
- into and out of nail-retaining relation to the discharge device, and means arranged to vary the position of the bar upon the arms. 5
12. In a nail-distributor, a nail-conveyor, a discharge device co-operating with the delivery-end of the conveyor, arms pivoted upon the conveyor, a stop-bar pivoted upon the arms, and means arranged to adjust the position of the bar upon its pivots. 10
13. In a nail-distributor, a raceway, an oscillatory discharge-roll having passages to receive the nails from the raceway and a surface over which the nails are delivered from the passages, an arm pivoted at each side of the raceway, a stop-bar carried by the arms above the roll-surface to move across the ends of the passages, and a cam turned with the discharge-roll and acting upon one of the arms. 15
14. In a nail-distributor, a raceway, an oscillatory discharge-roll having passages to receive the 20 nails from the raceway and a surface over which the nails are delivered from the passages, an arm pivoted at each side of the raceway, a stop-bar pivoted upon the arms, and means arranged to vary the angle of the stop-bar about its pivots. 25
15. In a nail-distributor, a raceway, a movable discharge-roll co-operating with the raceway, arms pivoted at opposite sides of the raceway, a stop-bar pivoted upon the arms and co-operating with the discharge-roll, a contact member arranged to determine the normal angle of the bar about its pivots, and a spring for maintaining the contact of said member. 30
